(57) **CLAIM**

I claim the ornamental design for the trim tool, as shown and described.

DESCRIPTION

FIG. 1 is a top perspective view of the trim tool;

FIG. 2 is a bottom perspective view thereof;

FIG. 3 is a side view thereof;

FIG. 4 is a top view thereof;

FIG. 5 is a side view thereof showing the side opposite that shown in FIG. 3;

FIG. 6 is a rear view thereof;

FIG. 7 is a bottom view thereof; and,

FIG. 8 is a front view thereof.

In the figures, dashed lines are used to illustrate features of the trim tool which form no part of the claimed design. In the figures, dash-dot-dash lines are used to illustrate boundary lines between the claimed and unclaimed portions of the design.
